UNITED STATES PATENT OFFICE.

ARTHUR STEIN, OF LONDON, ENGLAND.

MIXING-MACHINE.

No. 876,408.

Specification of Letters Patent.

Patented Jan. 14, 1908.

Application filed September 28, 1905. Serial No. 280,648.

To all whom it may concern:

Be it known that I, ARTHUR STEIN, chemical engineer, a subject of the Emperor of Austria-Hungary, residing at 36 Mark Lane, 5 in the city of London, England, have invented certain new and useful Improvements in Mixing-Machines, (for which I have applied for a patent in Russia, and which application is dated February 25, 10 1904, No. 23,334, and still pending, the Patent Office having taken no action thereon) of which the following is a specification.

This invention relates to a machine for making mixtures of saccharine liquids and 15 absorbents such as moss-peat and the like. By moss-peat is meant the product resulting from natural or artificial drying or humification of sphagnum moss and other peat-plants.

20 Moss-peat and similar substances mixed with molasses and other saccharine liquids are particularly adapted for feeding animals, horses, cattle, sheep and others. In mixtures the moss-peat, &c., acts as an absorbent and vehicle for the saccharine liquid. The production of such mixtures has hitherto 25 been a purely empirical process, no means having been known to vary the proportion of the constituents in accordance with their 30 varying qualities (humidity, purity, richness &c.), so that even in a given "batch" considerable differences in quality are apt to be found. By this invention such defects are remedied and perfectly uniform mixtures 35 are obtainable.

My improved apparatus is shown in the accompanying drawings in which:

Figure 1 is a longitudinal section of the whole. Fig. 2 a transverse section of the 40 mixer.

I provide a suitable vessel in which the saccharine liquid, say molasses is heated, such heater may be of any suitable construction and forming no part of my invention is 45 not shown in the drawings. When heated to a suitable degree the molasses or the like flow in to the regulator-vessel B. This vessel has a float S acting upon a valve k in the inlet pipe in such a manner as to maintain a constant level in B. The outlet pipe a is fitted 50 with a valve the key of which carries a handle a¹ which serves to open and close it and at the same time operates as an index moving over scale A¹ and this arrangement per-

mits the quantity of molasses delivered to be 55 accurately graded.

From the regulator vessel B the predetermined quantity of molasses continually flows into the mixer C. This is a trough like vessel with or without a steam-jacket and in it 60 rotates a feed screw C¹. The feed screw or conveyer may be of any suitable character having a continuous blade, or arms, or wings. At a suitable point in the mixer C there is an adjustable slide r passing over the shaft of 65 the conveyer, r¹ is a pin that enters one of the holes s in the slide to hold the same up. By raising or lowering the slide r the quantity passing under it can be regulated without altering the speed of the conveyer which receives uniform rotation from pulley-gear P. When the slide r and the valve in the pipe a are set the whole apparatus delivers a uniform product, in which the exact predetermined proportions between molasses, flowing 70 from the vessel B and absorbent fed into hopper V are present and constant. Such uniform mixture is then delivered from the outlet Z to a smaller conveyer Y which feeds the product to a drying apparatus or a drying 75 room for the purpose of drying either by heat or by mere turning over and over continued for a sufficient time, but the former is preferable.

By the use of the apparatus so constructed 80 I am enabled to make a product that will be always and in all respects uniform.

The following absorbents may be used; peat-moss, palm kernels, cocoa, rape seed, cotton seed or husk, earth-nut, sesame or 90 sunflower seed, poppy seed, maize, germs and other by-products or raw materials and waste products from manufacture of oils and fats; also hay, straw, or ground stems of various plants such as beans, beetroot seedlings, maize cobs, leaves, bran, rice, oat-husks, spent grains, marc, malt germs, hop residue, yeast residue, products of brewing distilling and wine making, sugar manufacture, bassia flour, bagasse, sawdust, beetroot 95 cuttings, and the like. The resulting molasses-fodder is advantageous in so far as it is a means for feeding animals with molasses in a dry form capable of easy manipulation.

Claims.

1. In a machine for producing uniform mixtures of saccharine liquids and absorbents a trough-like receiver, a screw conveyer

105

operating therein, a spindle and bearings for such conveyer, a regulator slide between the supply inlet and the mixing chamber said regulator slide embracing the conveyer spindle and means for adjusting the position of the regulator slide.

2. In a machine for producing mixtures of saccharine liquids and absorbents a regulator slide between the supply inlet and the mixing chamber said slide having a recess em-

bracing the conveyer spindle, means for adjusting the regulator slide and means for retaining it in position.

In testimony whereof I have hereunto set my hand in the presence of two witnesses. 15

ARTHUR STEIN.
